UNITED STATES PATENT OFFICE.

ANDREW SANFORD HANGER, OF FISHERSVILLE, VIRGINIA.

PACKING-PRESS AND BARREL-HEADER.

1,055,630.

Specification of Letters Patent. Patented Mar. 11, 1913.

Application filed June 21, 1912. Serial No. 705,143.

To all whom it may concern:

Be it known that I, ANDREW S. HANGER, a citizen of the United States, residing at Fishersville, in the county of Augusta and State of Virginia, have invented a new and useful Packing-Press and Barrel-Header, of which the following is a specification.

The device forming the subject matter of this application is a press adapted to be employed for compressing vegetables into barrels, the press being adapted to be employed in heading up the barrels after contents of the barrel have been compressed therein.

It is the object of the invention to provide novel means for assembling the constituent elements of the pressing mechanism, and to provide means for connecting the pressing mechanism operatively with the supporting frame.

A further object of the invention is to improve generally and to enhance the wearing qualities of, devices of that type to which the present invention appertains.

In the accompanying drawings, Figure 1 shows the invention in side elevation; Fig. 2 is an end elevation, parts being broken away; Fig. 3 is a vertical longitudinal section wherein divers parts appear in elevation; Fig. 4 is a transverse section on the line 4-4 of Fig. 2; and, Fig. 5 is a sectional side elevation of the presser foot and adjacent mechanism.

The base 1 comprises a platform 2 having depending feet 3 and 4. The platform 2 is surrounded by a retaining band 5. Upstanding from the platform 2, is a projection 6 which is shaped to fit in the lower end of the barrel 7 closely so as to reinforce the lower head of the barrel. The base 1 may be provided adjacent its corners, with depending hooks 50, adapted to receive a pair of parallel bars (not shown) whereby the structure may be carried about.

The supporting frame comprises arms 9 and an intermediate portion 10, there being an arched head 11 upstanding from the intermediate portion. Through the lower ends of the arms 9 of the supporting frame is passed a pivot element 12, preferably a bolt and nut structure. The pivot element 12 is passed through an opening 14 in the platform 2. A block 15 is mounted between the arms 9 of the frame 28 and abuts against the intermediate portion 10 of the frame, the arched head 11 being spaced apart from the upper face of the block 15. Securing ele-

ments 16 are extended through the arms 9 to engage the block 15, these securing elements 16 constituting pivots for the upper ends of the supports 17. The frame 28 may be swung to one side as indicated in dotted lines in Fig. 1, the supports 17 maintaining vertical positions and engaging the ground on both sides of the base 1 to uphold the frame 28 in a tilted position to one side of the barrel 7 so that the operator may fill the barrel readily and place the upper head 18 in the barrel after the barrel has been filled.

The compression mechanism includes a screw 20 provided at its upper end with an enlarged head 21, through which the turning bar 22 is removably thrust. The screw 20 is threaded through the arched head 11 and through the block 15.

The presser foot 23 is adapted to fit in the upper end of the barrel 7, the lower face of the presser foot 23 being equipped with a resilient facing 24, preferably fashioned from felt, the construction of the facing 24 being such that the fruit may be compressed in the barrel 7 without bruising or injuring the fruit. The upper face of the presser foot 23 has a recess 25 lined along its bottom and along its side walls with a metallic plate 26 having at its periphery a flange 27 which fits down flush with the upper face of the presser foot 23. To the upper face of the presser foot 23 a pair of retaining members 29 are secured by means of attaching elements 30 the retaining members 29 having in their meeting edges slots 31 defining a circular opening in which the screw 20 is journaled, the screw 20 having at its lower end a head 32 held for rotation within the retaining members 29, the plate 26 constituting a thrust bearing for the head 32. It is to be noted that the elements 30 not only secure the members 29 to the presser foot 23 but also enter the flange 28 of the plate 26, and hold the plate in position in the recess 25.

Operation: The frame 28 is tilted to one side as indicated in dotted lines in Fig. 1, until the supports 17 come into contact with the ground, thus maintaining the frame at an angle to the vertical and out of the way of the operator. A barrel 7 is then placed upon the platform 2, the projection 6 entering the lower end of the barrel with the chine and bearing against the lower head 8 of the barrel. The projection 6

prevents the lower head of the barrel from being bursted out under pressure and the head also serves to aline the barrel 7 vertically with the intermediate foot 4 so that when pressure is applied to the barrel, the pressure will be communicated to a reinforced portion of the platform 2. The barrel 7 is filled with the fruit or vegetables and the frame 28 is swung into vertical position as indicated in solid lines in Fig. 4. The screw 20 is then rotated through the medium of the turning bar 22, the screw 20 moving downwardly in the arched portion 11 of the frame and in the block 15 until the resilient facing 24 which is carried by the lower end of the presser foot 23 engages the fruit or vegetables whereupon the same, without bruise or injury, are thrust into the barrel 7, the head 32 carried by the lower end of the screw 20 obviously constituting means whereby the screw is swiveled to the presser foot 23. After the fruit has been compressed to the desired extent in the barrel 7, the presser foot 23 may be retracted from the fruit whereupon the upper head 18 is inserted into the barrel and thrust down into the chine by the presser foot 23.

Having thus described the invention what 30 is claimed is:

1. A press of the class described, comprising a base; a frame pivoted to the base; compression mechanism carried by the base; and a support pivoted to the frame and ly-

ing along one side of the frame, when the frame is upright, thereby to act as a reinforcement for the frame, to prevent the frame from springing laterally, the support maintaining a vertical position when the frame is swung to one side, thereby to constitute a prop supporting the compression mechanism to one side of a receptacle with which the compression mechanism cooperates, the prop constituting means for maintaining the compression mechanism in an inoperative position, and within reach of an operator.

2. In a press of the character described, a base; a frame pivoted to the base; a block located within the frame; a support; a connecting element passing through the support and through a portion of the frame, to enter the block, and constituting a means for maintaining the block in the frame, the support being pivotally mounted upon said element, whereby when the frame is swung laterally, the support will maintain an upright position and act as a prop to limit the tilting movement of the frame; and compression mechanism carried by the block.

In testimony that I claim the foregoing as my own, I have hereto affixed my signature in the presence of two witnesses.

ANDREW SANFORD HANGER.
